UNITED STATES PATENT OFFICE.

NORMAN V. CHRISTENSEN AND HAROLD J. LE VESCONTE, OF CHICAGO, ILLINOIS, ASSIGNEES TO UNION SPECIAL MACHINE COMPANY, OF CHICAGO, ILLINOIS, A CORPORATION OF ILLINOIS.

DESIGN FOR A SEWING-MACHINE FRAME.

Application filed September 23, 1924. Serial No. 10,888. Term of patent 14 years.

To all whom it may concern:

Be it known that we, NORMAN V. CHRISTENSEN and HAROLD J. LE VESCONTE, citizens of the United States, residing, respectively, at Chicago, in the county of Cook, State of Illinois, have invented a certain new, original, and ornamental Design for Sewing-Machine Frames, of which the following is a description, reference being had to the accompanying drawing, forming a part thereof.

Figure 1 is a top perspective view; and Figure 2 a front perspective view.

We claim:

The ornamental design for a sewing machine frame, as shown.

In testimony whereof, we affix our signatures.

NORMAN V. CHRISTENSEN.
HAROLD J. LE VESCONTE.
